poration of New York

Application April 18, 1938, Serial No. 202,602

8 Claims. (Cl. 72—127)

This invention relates to improvements in flashings, being directed specifically to through-wall flashing applied in building construction.

Up to the present time, considerable difficulty has been encountered in the use of corrugated, saw-tooth, or like flashings, by virtue of the fact that the portions thereof at the zone defining the "bend" between the horizontal and the vertical, are incapable of being bent without a cumbersome machine. Further, even with a machine the "bending" operation caused a flattening where a corrugated flashing is involved or a creasing where a zigzag flashing is involved, in either case preventing the proper passage of water seeping through the wall. Attempts have been made to obviate this difficulty; the flashing has been formed to provide a series of corrugated sections having therebetween flat surfaces defining the "bending" zones, but in eliminating the tendency to crack or a requirement for a machine the path for the flow of seepage water has been lost.

Generally, it is an object of this invention to provide a through-wall flashing of the corrugated or the like type, wherein "bending" zones are in the nature of sections corrugated in contour and forming continuations of the corrugations defining the vertical and horizontal sections of the flashing, such "bending" zone corrugation formation being of less angular degree, the respective corrugations defining the "bending" zone being so formed that the interior and exterior "bend" will at all times provide a continuous flow of seepage water through the valley.

These and other advantages, capabilities and features of the invention will appear from the subjoined detailed description of one specific embodiment thereof illustrated in the accompanying drawing, in which

Figure 1 is a plan view of a flashing strip prior to bending.

Figure 2 is an end elevation in section taken along lines 2—2 of Figure 1.

Figure 3 is an end elevation in section taken along lines 3—3 of Figure 1.

Figure 4 is a front elevation in section taken along lines 4—4 of Figure 1.

Figure 5 is an end elevation in section taken along lines 5—5 of Figure 1.

Figure 6 is a front elevation in section taken along lines 6—6 of Figure 1 showing the flashing sheet as applied in a course of masonry.

Referring to the reference characters in the drawing, the flashing sheet shown in plan in Figure 1 is formed by stamping to provide cor-

rugations extending transversely across the same, said corrugations comprising continuous ridge and valley formations normally of equal amplitude and extending on opposite sides of the central horizontal plane of the sheet.

The corrugations on the flashing sheet, particularly the alternate ridges A and the valleys B defining the same, are continuous transversely across the flashing sheet, except that a change in amplitude of either or both of the ridge and valley formations with respect to the normal equal amplitude of the same is provided in spaced zones or areas indicated as 10, 11, 12 and 13 in Figure 1, such zones or areas having the ridge and valley formations such that the amplitude of either of the same and the total of the two is less than the amplitude thereof in the remainder of the corrugations spaced and connected by such zones, such difference in amplitude permitting for ease in bending of the flashing as required.

To illustrate, referring to Figures 1 to 3 inclusive, the amplitude of the ridges A and valleys B of the sections 14, 15, 16, 17 and 18, leading to and connected by zones 10, 11, 12 and 13 are equal and opposite; whereas along zones 10 and 12, the ridges A' in such zones are continuations of and have the same amplitude as those in sections 14, 15, 16 and 17, while the valleys B' in such zones are flattened and of less amplitude than those of sections 14—15, and 16—17; while with respect to zones 11 and 13, the valleys B'' of such zones are continuations of and have the same amplitude as those in sections 15—16 and 17—18, and the ridges A'' in such zones are flattened and of less amplitude than those of sections 15—16 and 17—18.

This lessening in amplitude respectively of the valleys B' in zones 10 and 12 and the ridges A'' in zones 11 and 13, as shown in detail in Figures 2 and 3, is more aptly illustrated functionally in the section of a flashing sheet bent longitudinally along its length at the zones aforesaid to provide up bends with respect to the first named zones, as illustrated by letters C in Figure 6, and down bends in the second named zones as illustrated by the letters D in Figure 6.

As indicated in such figure the ridge and valley formation extending along such zones 10 to 13 is of less combined amplitude than that of the ridges and valleys of sections 14 to 18; in the first named zones the ridges being of less amplitude than the valleys, and in the second named zones the valleys being of less amplitude than the ridges, providing a zone or area of less depth for bending between the connected deeper corrugated

- sections 14 to 18, wherein the ridges and valleys defining the corrugations are regular in amplitude. By virtue of the spacing or zone formation having a lessening of amplitude respectively 5 of the valleys and ridges without breaking the continuous corrugated contour, the desired bending may be accomplished while as indicated in Figure 6 the path along the valleys for seepage of water is maintained, the valley at all times 10 being lower than the lowermost portion of the adjacent ridge to thus provide a continuous path of flow for seepage water as the flashing is bent for an installation, shown partially broken away in Figure 6.
- 15 As shown in Figures 1 and 3, some of the ridge formations have stamped depressions 19 formed therein, the same being spaced and serving as locking formations to bond the flashing as it is embedded in plaster between a masonry course 20 to prevent the flashing from horizontal or lateral displacement.

The flashing sheets, being of corrugated conformation, may be interlocked at their lateral ends to provide a continuous length applicable 25 for use in building construction, the respective depressions forming the bonding elements serving as guides in conjunction with the normal corrugated formation of the flashing sheets to maintain the interlocked sheets from lateral displacement or separation.

It is obvious that various changes and modifications may be made to the details of construction without departing from the general spirit of the invention as set forth in the appended 35 claims.

I claim:

1. A through wall flashing sheet having transverse corrugations extending continuously thereacross, said corrugations being interrupted as to 40 contour along their length by short sections of different amplitude than that of the remaining long sections connected thereby, said short corrugated sections serving as longitudinal bending zones for said flashing sheet.
- 45 2. A through wall flashing sheet having continuous transverse corrugations extending thereacross, said corrugations being interrupted as to contour by spaced short sections of different amplitude than that of the remaining sections connected thereby, said short corrugated sections defining a continuous longitudinal area and serving as longitudinal bending zones for said flashing sheet.
- 50 3. A through wall flashing sheet having continuous transverse corrugations defining alternate ridge and valley formations extending thereacross, said ridge and valley formations of said corrugations being interrupted as to contour along their length by short sections of different 55 amplitude than that of the long sections connected thereby, said short corrugated sections defining a continuous longitudinal area and serving as longitudinal bending zones for said flashing sheet.
- 60 4. A through wall flashing sheet having continuous transverse corrugations defining ridge and valley formations extending thereacross, said corrugations being interrupted alternately as to contour along their length by short sections of 65 corrugations, wherein successively the ridges and valleys are of different amplitude than that of the long sections connected thereby, said short

corrugated sections defining continuous longitudinal areas serving successively as bending zones for said flashing sheet to provide a predetermined zigzag right angular conformation of the flashing sheet upon bending.

5 5. A through wall flashing sheet having continuous transverse corrugations defining alternate ridge and valley formations extending thereacross, said ridge and valley formations of said corrugations being interrupted as to contour 10 along their length by short sections of different amplitude than that of the long sections connected thereby, said short corrugated sections defining a continuous longitudinal area and serving as longitudinal bending zones for said flashing sheet, the valleys of the corrugation being 15 so formed to provide at all times a continuous transverse trough for seepage water along the length and at the bending zones.

6. A through wall flashing sheet having continuous transverse corrugations defining ridge and valley formations extending thereacross, said corrugations being interrupted alternately as to contour along their length by short sections of corrugations, wherein successively the ridges and 25 valleys are of different amplitude than that of the long sections connected thereby, said short corrugated sections defining continuous longitudinal areas serving successively as bending zones for said flashing sheet to provide a predetermined zigzag right angular conformation of the flashing sheet upon bending, the valleys of the corrugation being so formed to provide at all times a continuous transverse trough for seepage water along the length and at the bending 30 zones.

7. A through wall flashing sheet having continuous transverse corrugations comprised of ridge and valley formations extending thereacross, said transverse corrugations being shaped 40 to provide lengths having common amplitude of the ridge and valley formations spaced by and connected to shorter lengths, wherein either the ridge or valley formations are of lesser amplitude than the other, the last named shorter 45 lengths extending longitudinally along the flashing sheet and providing a longitudinal bending zone.

8. A through wall flashing sheet having continuous transverse corrugations comprised of ridge and valley formation extending thereacross, said transverse corrugations being shaped to provide body lengths having common amplitude of the ridge and valley formations spaced by and connected to shorter lengths, wherein either the 55 ridge or valley formations are of lesser amplitude than the other, the last named shorter lengths extending longitudinally along the flashing sheet and providing a longitudinal bending zone, the ridge and valley formations of successive shorter lengths being such that the ridge of one of said connecting shorter lengths is a continuation of the ridge of the spaced body lengths leading thereto, while the valley of said shorter length is of lesser amplitude than that 60 of the valley of the body length leading thereto, while as to the next connecting shorter length, the valley thereof is a continuation of that of the body length leading thereto, and the ridge thereof is of lesser amplitude than that of the 65 ridge of the body length leading thereto.
